(57) **CLAIM**

The ornamental design for a breeder box assembly, as shown and described.

DESCRIPTION

FIG. 1 is a left, front perspective view of a breeder box assembly shown according to the present design;

FIG. 2 is a right, rear perspective view thereof;

FIG. 3 is a front end view thereof;

FIG. 4 is a rear end view thereof;

FIG. 5 is a left side elevational view thereof;

FIG. 6 is a right side elevational view thereof;

FIG. 7 is a top plan view thereof; and,

FIG. 8 is a bottom plan view thereof.

The broken line representations illustrate unclaimed environment and boundaries. The broken line representations thus form no part of the claimed design.

1 Claim, 4 Drawing Sheets(56)
